Des. 221,906
Patented Sept. 14, 1971

221,906

WRITING IMPLEMENT

Joseph J. Collins, Los Angeles, Calif. (15050 Burbank Blvd., Van Nuys, Calif. 91401), and Pasqual F. Fortugno, Los Angeles, Calif.; said Fortugno assignor to said Collins

Filed Apr. 16, 1970, Ser. No. 22,466

Term of patent 14 years

Int. Cl. D19—06
U.S. Cl. D74—17

FIG. 1 is a perspective view of a writing implement showing our new design;

FIG. 2 is a side elevational view thereof;

FIG. 3 is an end view as seen from the left of FIG. 2;

FIG. 4 is an end view as seen from the right of FIG. 2;

FIG. 5 is a side elevational view of another embodiment of the writing implement shown in FIG. 1 wherein the clip and push button have been omitted and the top end has been rounded;

FIG. 6 is an end view thereof as seen from the left of FIG. 5; and

FIG. 7 is an end view thereof as seen from the right of FIG. 5.

We claim:

The ornamental design for a writing implement, substantially as shown and described.
